FRACTIONATION OF MIXTURES OF FATTY OILS AND FREE ACIDS DERIVED THEREFROM

John D. Jenkins, Forest Hills, Pa., assignor to Pittsburgh Plate Glass Company, Allegheny County, Pa., a corporation of Pennsylvania

Application May 13, 1940, Serial No. 335,007

12 Claims. (Cl. 260—428)

The present invention relates to processes of fractionating glycerides of the higher fatty acids and to the fractionating of mixtures of free acids derived from such glycerides, and it has particular relation to the fractionation of such compounds by selective liquid phase extraction with a polar solvent which has a higher degree of solvency for certain components of the mixture than for others.

One object of the invention is to provide a process of the foregoing type which can be conducted at a substantially higher temperature than is permissible by other processes, which is less subject to temperature fluctuations than processes heretofore available and which can be operated without danger of solidification of low melting point materials.

A second object of the invention is to provide a process which permits of a relatively high output for a given amount of apparatus.

A third object of the invention is to obviate the necessity of dehydrating the solvent in order to remove the accumulations of water from the material extracted.

A fourth object of the invention is to reduce the amount of solvent required in making extractions in the foregoing process.

It is recognized that most of the animal and vegetable oils comprise mixtures of glycerides of various fatty acids. Among the oils of this type may be included linseed oil, soya bean oil, perilla oil, marine oils, such as sardine, menhaden, cod, halibut and whale, cottonseed oil, peanut oil, corn oil, sunflower seed oil, olive oil, tallow, lard and the like. In most instances the glyceride components of these oils differ from each other primarily in the degree of saturation or unsaturation or the position of the unsaturated valences in the acid residues. However, certain other oils of the type of coconut oil, palm oil and the like comprise mixtures of glycerides, the components of which to some extent differ from each other by reason of variances in the degree or manner of unsaturation but probably to a greater degree differ by reason of differences in the chain length of the acid radicles or residues in the esters. Of course, the free fatty acids existing in or derivable from these oils differ from each other to a substantial degree in the same manner as the glycerides from which they are derived.

In copending applications Serial Nos. 144,315, now issued as Patent 2,200,390, filed May 22, 1937, and 251,340, now issued as Patent No. 2,200,391, filed January 17, 1939, both to Stephen E. Freeman are disclosed processes of separating glycerides of the foregoing types and the free fatty acids from such glycerides into fractions which are relatively enriched in certain components of the mixtures and correspondingly impoverished

in other components. These processes are based upon a preferential solvent action of organic polar solvents for the more highly unsaturated or more actively unsaturated components of the mixtures or for the components of shorter chain length. By reason of such process it is possible by the proper contacting of the oils of free acids with the solvents to obtain two liquid phases, one consisting essentially of raffinate oil or free fatty acid with a certain proportion of selective solvent dissolved therein and the other consisting mainly of solvent with a fraction of the material to be extracted in solution.

The more unsaturated material or actively unsaturated material, or material of shorter chain length is to be found dissolved in the solvent, whereas the more saturated materials and longer chain length materials remain out of solution, but to a certain extent become saturated with the solvent. According to the processes these liquid phases may be separated from each other by settling and decantation or by centrifugation and upon elimination of the solvent, for example, by distillation fractions of oils or free fatty acids therefrom are obtained, which differ for example by reason of iodine value or molecular weight. Upon application of such process to drying and semi-drying oils, it is possible to obtain fractions which are relatively highly unsaturated, as compared with the original oil and which esters possess substantially enhanced drying properties. Therefore, their value for use in paints, varnishes, and the like is increased. Simultaneously, of course, there is obtained a fraction which is of lower iodine value and which is particularly applicable for use in food products and other such uses where high iodine value is not required, or is objectionable. More completely saturated materials, such as cottonseed oil may also be fractionated to obtain fractions which are especially useful for foods and perhaps in some cases to obtain fractions to possess drying properties. These of course are merely examples of the application of the broad process of invention.

The present invention is based upon the discovery that the polar solvents as disclosed in the foregoing applications and other solvents of similar properties may in many cases be incorporated with a second material, which at least to some degree is miscible in the solvent, but is a non-solvent for the glycerides previously mentioned or the free fatty acids derivable therefrom, in order substantially to modify the properties of the solvent. In general where a non-solvent for oil or free fatty acid, such as water, is employed in conjunction with the polar solvent, it is found that the temperature of miscibility with the oil or acid is substantially increased so that liquid phase extraction can be conducted at

a substantially higher temperature than is otherwise permissible. Also, in many cases where the polar solvent possesses a considerable degree of solubility for all components of the oil the selective action of the pure solvent is found to be so masked that fractionation of oils and free fatty acids into components cannot be effected. However, by the addition of a judicious amount of a non-solvent for the oil or acid, e. g. water, which, however, is soluble in the polar solvent, it is possible so to lower the general solubility of the oil or acid as to admit of separating the mixture into two liquid phases.

It, of course, will be apparent that the extraction must be so conducted that the solvent employed in the process will exert a certain degree of solvency for the oil or the free acid to be extracted, and it, also, must be of polar nature or possess certain polar groups as disclosed in the foregoing applications, so that it will exert a preference for the more unsaturated or actively unsaturated components or the short chain length components of the mixtures to be treated. It must also possess at least some solubility with water. The following are examples of a series of organic polar solvents which are contemplated as being within the scope of the present invention:

Table A

Hydroxyl	Hydroxyl—Other
Methyl alcohol	Allyl alcohol
Ethyl alcohol	Ethylene chlorhydrin
n-Propyl alcohol	Glycerol monochlorhydrin
iso-Propyl alcohol	Beta, gamma-dibromo propyl alcohol
Ethyleneglycol	Beta-hydroxy propionitrile
Propylene glycol	Beta-ethoxy ethyl lactate
Glycerine	Beta-ethoxy ethyl glycolate
Hydroxyl—Ester	Furfural alcohol
Methyl glycolate	2-nitro-1-butanol
Ethyl glycolate	Acid
Beta-hydroxy ethyl acetate	Formic acid
Ethyl lactate	Acetic acid
Mono acetin	Ester—Carbonyl
Diacetin	Methyl levulinate
Hydroxyl—Carbonyl	Ethyl levulinate
Methyl butanolone	Methyl acetoacetate
Acetyl methyl carbinol	Ethyl acetoacetate
Diacetone alcohol	Isopropyl acetoacetate
Methyl acetyl lactate	Aldehyde
Ester	Acetaldehyde
Methyl formate	Aldehyde—Other
Ethyleneglycol formate	Methoxy acetaldehyde
Tracetin	Furfural
Glycol diacetate	m-Nitrobenzaldehyde
Methyl malonate	Carbonyl
Methyl oxalate	Acetonyl acetone
Ethyl oxalate	Amine
Ester—Other	Diethylene triamine
Methyl cellosolve formate	Triethylene tetramine
Methyl cellosolve acetate	Nitrile
Methyl cellosolve adipate	Propionitrile
Dimethyl cellosolve succinate	Esters of inorganic acids
Ethyl n-methyl carbamate	Trimethyl phosphate
Methyl chloroacetate	Triethyl phosphate
Methyl cyanoacetate	Beta-methoxy ethyl carbonate
Amides	Dimethyl sulfate
Formamide	
Acetamide	
Propionamide	
Butyramide	
Nitro	
Nitromethane	
Nitroethane	
Hydroxyl—Ether	
Methyl cellosolve	
Cellosolve	
Diethylene glycol	
Triethylene glycol	
Carbitol	
2-hydroxy-methyl-1,3-dioxolane	

All of the polar solvents above listed are capable within themselves of forming immiscible systems with various drying or semi-drying oils, such as soya bean oil, at a temperature above about 0°

C. However, if they are warmed the oil and the solvents become completely miscible, but upon cooling they will separate into phases in the manner previously described. The proportion of oil remaining in the solvent will depend upon the temperature and may vary according to the requirements placed upon the fraction which is to be separated by extraction.

The following constitutes a partial list of solvents which are miscible with glyceride oils at temperatures down to zero degrees, but which can be admixed with water in substantial amounts, in order to form systems immiscible with oils and acids.

Table B

	Hydroxyl	Carbonyl
15	Tertiary-butyl alcohol	Acetone
	Hydroxyl—Ether	Ether
20	Butyl cellosolve	Dioxane
	Butyl carbitol	Dioxolane
	Hydroxyl—Double bond	Dimethyl cellosolve
	Phenol (M. A. P.—66° C.)	Dimethoxy tetraglycol
	Hydroxyl—Triple bond	
25	Dimethyl ethynyl carbinol	Ether—Imino
	Hydroxyl—Halogen	Morpholine
	Propylene chlorhydrin	Amino (or imino) 1
	Hydroxyl—Other	Piperidine
30	Diethyl aminoethanol 1	Amino (or imino)—Double bond
	Carbonyl	Pyridine 1
	Propionic acid	
	Isobutyric acid	

1 These react with free fatty acids and are not suitable for use therewith.

In the operation of the process the free fatty acids or oils to be extracted may be merely admixed with the desired solvent containing a suitable proportion of water. If the admixture is effected at a temperature above that of miscibility of the acid—solvent mixture or if the mixture of incompletely miscible solvent and free fatty acids or oil is brought to a higher temperature, it will be apparent that the system will become completely miscible. However, upon cooling the system below the temperature of miscibility separation into phases will occur. One phase will consist of solvent saturated with extracted glycerides or fatty acids which are substantially enriched in one component of the said mixture. The other phase will comprise essentially the less soluble component of the mixture saturated with a certain amount of solvent.

Obviously as the completely miscible solution of free fatty material and solvent is cooled down more and more of the acids in the extract phase will be thrown out and correspondingly the raffinate phase will be increased. As the size of the fraction in solution in the solvent is reduced by lowering of the temperature it is obvious that the fraction still remaining in solution will be enriched in the more soluble components of the free fatty acids or oil. However, the yield of extracted acids or oil, of course, is reduced. Therefore, in practicing the invention it is desirable merely to reduce the temperature until a fraction of desired proportions or of desired constituency is retained in the solvent. After separation of the mixture as distinct phases, the latter may be removed from each other, for example, by allowing them to settle into liquid layers and then decanting or otherwise removing the layers, or by centrifugating the mixtures of phases in an appropriate apparatus.

In general the separation of the liquid phases from each other will be effected at a temperature within a range of about 2 to 40° C. below that of complete miscibility of the solvent-fatty acid or oil mixture. The temperature of complete miscibility of any particular system of solvent and fatty acid is easily determinable by merely admixing samples of the oils or free fatty acids with wet solvent and warming the resultant mixture until it becomes completely miscible. Subsequently the mixture may be cooled until it tends to separate into phases as evidenced by the formation of a haze or cloud.

The ratio of wet solvent to oil may vary over a relatively wide range, for example, of 1 to 1, up to 10, or even more of solvent to 1 part of fatty acid or oil.

Soya bean oil was extracted with wet acetone, the ratio being 1 to 4. The results are tabulated as follows:

	Water 3.1%	Water 0.5%
Temp. of sepn. .... °C.	27	0
Per cent extract.	41	57
Per cent raff.	59	43
I. V. ext.	139.6	139.0
I. V. raff.	132.8	131.5
I. V. orig. oil	136	136
Diff.	6.8	7.5

In a study of a selective polar solvent, namely furfural, various oils including alkali refined soya bean oil, alkali refined linseed oil, varnish makers perilla oil, sardine oil, cottonseed oil and refined coconut oil were treated in the following manner: 175 parts of oil and 875 parts of furfural, which had been saturated with water at normal room temperature were intimately contacted with each other. The mixture was then held at separation temperature until the liquids definitely parted and the extract layer was then drained off. The solvent in the two fractions was removed by vacuum distillation. The results of the tests are tabulated as follows:

	Wet furfural					
	Linseed	Perilla	Soya	Fish	Coco-nut	Cotton-seed
Temp. misc., °C	84	70	95	84	70	96
Temp. sep.	70	58	82	74	60	84
I. V. ext.	185	211	136	210	12.3	110
I. V. raff.	169	201	126	188	19.8	103

Percent yield ext.	55.7	47.8	41.2	50	51.4	35.7

NOTE.—Linseed oil and soya bean oil were alkali refined.

The effect of water on increasing the temperature of miscibility of furfural on various oils is shown by the following table in which the temperatures of miscibility of the oils in wet and dry furfural are compared:

Oil	Soy-bean	Lin-seed	Coconut		Perilla	Re-fined fish oil	Cot-ton-seed
			#1	#2			
Temp. misc. anhyd. °C.	51	37	31	31	24	37	53
Wet.	95	84	70	60	70	84	96
Inc. in temp. due to water.	44	47	39	29	46	47	43
Iodine value oil.	132	179	15	10	208	203	107

The effect of varying the amounts of water on the temperature of miscibility of the various oils and furfural is shown by the following table:

5	Percent water by vol. in furf.	Fish oil	Soy-bean	Linseed	Coco-nut
0		37	51.5	35.5	29
1		46	59	44.5	37
2		54	67	53	45
3		61	74	61	53
4		68	81	69	60.5
5		75	88	76	68
6		81	94	83	75
7		84	98.5	90	81
8		87	100.5	95	88
9		90		99	92
10					96

In the preceding table oil and furfural were contacted in the ratio of 1 part of oil for each 5 parts of anhydrous furfural.

The wet solvents may also be employed at appropriate temperature in the fractionation of free fatty acids of the foregoing oils or similar oils. However, the rise in the miscibility temperature of the mixture is substantially less pronounced than in the class of the glyceride oils themselves. In this operation the acids preferably are dissolved in about 25 to 200% of petroleum naphtha or other hydrocarbon not miscible with furfural.

The results obtained by extracting mixtures of free fatty acids of soya bean oil are tabulated below:

Selectivity of wet furfural vs. dry furfural with free soya acids in 25% of naphtha

35		Anhydrous furfural	Wet furfural
Temp. misc. .... °C		61	79
Temp. sep.		50.5	68
I. V. ext.		141.7	141.0
I. V. raff.		123.0	128.2
I. V. orig.		135.8	135.8

A. V. ext.		157.4	197.5
A. V. raff.		198.0	196.5
A. V. orig.		196.1	196.1

As previously indicated various processes and apparatuses may be employed in effecting the contact of the solvent and the oil or free fatty acid to be extracted. The apparatus disclosed in the drawing constitutes an example of one suitable form.

The apparatus as disclosed includes an extraction tower or column 10 which may be packed with Raschig rings or Berl saddles, etc., and may be of substantially any diameter dependent upon the quantity of glycerides or acids to be passed therethrough. The height of the column preferably is approximately within the range of 30 to 50 feet. However, these limits may be substantially exceeded, if so desired. It also is provided with a cover or jacket 11, which, as shown, may be formed in separate sections, such as 12, 13 and 14, and may be of substantially any number dependent upon the gradation of temperature within the column which it may be desired to maintain. The sections may be supplied with heat exchange medium, such as water or the like through inlets 16 and outlets 17. The inlets may be connected to separate sources of heat exchange medium at different temperatures, or if preferred they may all be connected to a single source. Also, as shown in the drawing, the outlet conduit may be connected by a conduit 18 with the inlet conduit of the adjacent section. The various con-

duits are supplied with valves 19, which may be opened or closed to admit of the circulation of the heat exchange medium through each section of the jacket individually or to cause the fluid to flow from the outlet of one section to the inlet of the adjacent section as may be desired.

Glyceride oil or free acids of glyceride oils may be stored in a container 21, which, also, may be provided with a jacket 22 by means of which it may be maintained at any desired temperature. Hydrocarbon, such as naphtha, may be added through conduit 22a. Oil from the container flows through conduit 23 and is forced by suitable pump 24 into an intermediate portion of the column 10, preferably at a distance of about 12 feet from the bottom of the column.

Solvent for the extraction may be stored in a container 25 and is fed through conduit 26 to a pump 27, connected to conduit 28 in a heater jacket 29, having at one extremity an inlet 31 for heated fluid such as water and at the opposite extremity an outlet 32 for the waste fluid. In some instances it may be desirable to add water or other fluid at least partially miscible with the solvent, but immiscible with the material to be refined, in order to reduce miscibility thereof in the solvent. Such addition may be made through conduit 32a. The upper extremity of conduit 28 discharges into the upper extremity of the column 10 at a short distance from the top thereof. Inert gas such as CO₂ may be supplied to blanket the solvent through conduit 32b.

It will be apparent that by reason of the difference in specific gravity of the solvent and the glyceride oil or the acids derived therefrom the two liquids will tend to flow countercurrently with respect to each other. Assuming that the solvent is the heavier component it will descend while the undissolved oil will rise. Therefore, in a zone 33 extending approximately from the inlet for the solvent down some distance below the inlet for the glyceride oil or the acids, there will be a mixture of countercurrently flowing components. Also, the oil will be carried by the solvent a certain distance below the oil inlet. In the zone of countercurrent flow of selective solvent and oil or acid it will be apparent that there is very intimate contact, and the selective solvent gradually extracts a fraction which is rich in the more soluble component, such as the more unsaturated or actively unsaturated glycerides and acids, or the glycerides or acids which are more soluble by reason of differences and chain length in the molecule. The less soluble components of the oil do not dissolve in the solvent, at least not completely but do tend to take up a certain amount of the solvent. In a zone near or slightly above the inlet for the conduit 28 the less soluble component or raffinate will form a layer or body 36 of insoluble glyceride oil, or oil acid, which is saturated or substantially saturated with solvent and may be drawn off through a conduit 37, that leads to suitable apparatus (to be later described) for the separation of the solvent dissolved therein. Inert gas is admitted through conduit 37a to blanket the raffinate.

The undissolved solvent with the extract phase therein ultimately separates out in the bottom of the column as a distinct layer or fraction 39, which may be drawn off through a conduit 41, that extends upwardly a sufficient height to admit of hydrostatically balancing of the liquid therein against the liquid contained in the extraction column 10.

Since the solvent and the oils are of different specific gravity, and since under varying conditions there will be a tendency for the relative amounts thereof in the column 10 to vary somewhat, it is desirable to provide at the upper extremity of the conduit 41 a section 42 which can be elevated or lowered to accommodate for the variations, thus making it possible to assure that the various strata in the column 10 are approximately at the desired levels. The upper extremity of the adjustable section 42 is provided with a head 43, in which the pressure may be atmospheric. This head is filled with inert gas through conduit 43a.

15 The solvent charged with extract discharges through this head to a conduit 44 leading to the upper extremity of a flash vaporizing column 46, provided with a jacket 47 to which steam at a pressure of 20 or 30 pounds per square inch or other heat exchange medium may be admitted through conduit 48 and from which spent medium is discharged through conduit 49. The oil is delivered into column 46 as a shower or spray that falls into a spray trap 51 in which the droplets of separated oil, largely freed of the solvent, are collected. The column 46 preferably is maintained under partial vacuum, e. g. under a pressure of 100 or 300 m. m. Vaporization of solvent in the column is almost instantaneous. The solvent vapors pass off from the trap through conduit 52 to a condenser 53, which in turn discharges through conduit 54 and pump 56 back to the solvent container 25.

20 The extract separated from the vaporized solvent in the trap is discharged through conduit 57 to a surge tank 58, having inlet 59 for inert gas. From the tank, it, or any suitable portion thereof, is discharged through conduit 61 to stripping apparatus (to be described later) for removal of the last traces of the solvent contained therein. A portion of the extract with the small amount of solvent therein is discharged through conduit 62 to pump 63, which forces it through conduits 64 back into the column 10 at a point 25 preferably below the feed oil inlet, but slightly above the upper limit of the separated solvent phase in the lower portion of the container. The concentration of the more soluble component is thus increased in a zone adjacent to solvent-extract layer and this results in the separation of 30 more of the less soluble component from the oil so that ultimately an extract is obtained, which is richer in the more soluble component and poorer in the less soluble component, than would otherwise be obtained. Substantially any ratio 35 of the extract, for example 10 to 90% of the extract may be recycled.

35 The extract separated from the vaporized solvent in the trap is discharged through conduit 57 to a surge tank 58, having inlet 59 for inert gas. From the tank, it, or any suitable portion thereof, is discharged through conduit 61 to stripping apparatus (to be described later) for removal of the last traces of the solvent contained therein. A portion of the extract with the small amount of solvent therein is discharged through conduit 62 to pump 63, which forces it through conduits 64 back into the column 10 at a point 40 preferably below the feed oil inlet, but slightly above the upper limit of the separated solvent phase in the lower portion of the container. The concentration of the more soluble component is thus increased in a zone adjacent to solvent-extract layer and this results in the separation of 45 more of the less soluble component from the oil so that ultimately an extract is obtained, which is richer in the more soluble component and poorer in the less soluble component, than would otherwise be obtained. Substantially any ratio 50 of the extract, for example 10 to 90% of the extract may be recycled.

55 As previously stated the inlet for the recycled oil is slightly above the level of the separated solvent and preferably it is at such distance below the level of the inlet for the oil that the recycled oil, as it passes upwardly through the solvent, will reach approximately the same composition as the feed oil from the container 22. 60 Assuming that furfural is employed as the selective solvent the distance between the inlets of the feed oil and the recycled oil may be approximately 12 feet. The distance between the inlets for the feed oil and the solvent may vary over 65 a substantial range, but preferably is about 15 to 35 feet.

65 If preferred, separation of the extract from the solvent may be effected by addition of water, e. g. 3 to 15% of water or other non-solvent, at 70 a temperature below that of miscibility. The

vaporizer 46 may then be eliminated or may be by-passed by conduit 65 interconnecting conduit 44 and conduit 57. Separation of the extract may be effected in the latter by addition of water through conduit 65a. Where wet furfural is used, the oil may be simply cooled in order to effect stripping of solvent without addition of more water.

The apparatus for removing the dissolved solvent from the raffinate includes a vaporizer column 66 into the upper extremity of which the conduit 31 discharges the raffinate as a spray. The column is provided with a heating jacket 61, which is supplied with steam or other heated fluid by means of conduit 68 and the spent fluid is discharged from the jacket through conduit 69. The pressure within the column 66 like that in column 46 is subatmospheric—e. g., about 100 to 300 m.m. of mercury and evaporation of the most of the solvent is almost instantaneous. At its lower extremity the column discharges into a conventional spray trap 71, in which the droplets of raffinate from which much of the dissolved solvent has been evaporated are collected.

The solvent freed of raffinate and in vapor state is discharged through a conduit 72, to a line 73 leading to a condenser and source of vacuum (not shown). The raffinate, separated from the vapors in the trap 71 and still containing some solvent, is discharged through conduit 74 into the upper extremity of a stripping column 76, which column is provided with a jacket 77 supplied with steam or other heated fluid through conduits 78, having a connection to a line 79. Where steam is employed the pressure is preferably about 50 lbs. per square inch corresponding to about 280° F. The spent fluid is discharged from the bottom of the jacket through conduit 81.

Column 76 preferably is packed with an inert material such as Raschig rings, Berl saddles or other packing material designed to check the descent of the oil and to cause it to be spread out into thin films presenting large surfaces. Steam or other distilling medium is introduced at the bottom of the column through conduit 82 and passes upwardly through the packing in such manner as intimately to contact with the surface of the oil and thus to carry away any solvent dissolved therein. The steam passes out of the column more or less completely charged with solvent through conduit 83 and is discharged into the line 72. The raffinate oil now freed of solvent is discharged through conduit 84 at the bottom of the column and is passed to storage or is passed on for further treatment, for example, for an additional extraction in further stages of apparatus. Such stages obviously may assume substantially the form of the apparatus herein disclosed and by such treatment it is possible to remove an additional fraction or fractions of more soluble component from the raffinate.

The conduit 61 carrying the more soluble or extract components of the glyceride oil or the acids thereof, namely the more unsaturated components, is discharged into a second stripping column 86 substantially corresponding in construction to the column 76 and having a jacket 87 for steam or other fluid as previously described in connection with the column 76. The column is also packed as indicated at 88 and is supplied with steam through conduit 89. Steam discharged with solvent discharges from the upper extremity of the column through conduit 91, which also discharges into the vapor line 73

and passes on to suitable apparatus for separation of the solvent from the water vapors. The component of the oil which initially is dissolved in the solvent and which is liberated in the column 86 is discharged from the bottom of the latter through a conduit 92, is either passed to storage or is subjected to further treatment, for example, to further fractionation in additional stages of apparatus in order more completely to separate out any saturated or less soluble components which may be carried therein. In this way a fraction which is very rich in unsaturates or other component, which is selectively soluble in the solvent employed, may be obtained.

15 The fractions as obtained in the present process are susceptible of very broad application. For example, it is possible to separate soya bean oil into a relatively unsaturated fraction which has good drying properties and may be employed as a substitute for more expensive linseed oil. At the same time there is obtained a raffinate fraction which is relatively low in unsaturates and this fraction is particularly useful in food products such as shortenings, margarine, salad oils, or in soaps and the like. Heretofore the use of soya bean oil in food products has been somewhat restricted by reason of the fact that it tended to become rancid, by reason of certain chemical reactions occurring therein. It has been found that soya bean oil fractionated by the process as herein disclosed is greatly improved in this respect. It will, of course, be apparent that the oil is improved as a food product for certain purposes, because the more highly saturated components have substantial higher melting points than the less saturated components. Therefore, it is possible to separate out a fraction having higher melting points than the initial oil, which fraction is well adapted for use in shortenings and the like. Of course the saturated raffinate fraction is well adapted for use in soaps in which the unsaturated are to be avoided. In soap products development of rancidity by reason of chemical change is also objectionable and since the raffinate obtained by the present process exhibits less tendency to become rancid it is particularly useful therein.

50 Either the raffinate or the extracted oils or the free acids of the oils herein disclosed may be subjected to hydrogenation by appropriate processes. For example, they may be confined in an autoclave under pressure and hydrogenated to a suitable degree in the presence of a catalyst of hydrogenation, such as finely-divided nickel or the like.

55 The extracted oils as obtained from linseed, soya bean, marine oils, perilla oil and others containing substantial amounts of glycerides susceptible of air drying are excellently adapted for use as drying oils in the fabrication of paints and varnishes. By application of the extraction process extracted oil having good drying properties and sufficiently free of objectionable matter, such as free acids, anti-oxidants break-producing constituents and the like can be obtained without subjecting the oil to severe treatment with acid or alkali. In the fabrication of paints and varnishes the conventional pigments, colors, thinners and the like are added as with conventional drying oils. For example, titanium oxide, lithopone and other pigments may be added in amounts of 5 to 60%. Turpentine or any other volatile thinner may be also added in an amount of 10 to 25%.

70 75 The forms of the invention herein disclosed

are merely representative. Numerous modifications can be made therein without departure from the spirit of the invention or the scope of the appended claims.

What I claim is:

1. A process of separating into fractions a material selected from a class consisting of glyceride oils and free fatty acids derived from such oils, which material comprises components, one of which is of relatively high polar moment and another of which is of relatively low polar moment, which process comprises contacting the material with a non-reactive solvent mixture containing a selective polar solvent and a substantial amount of water dissolved therein at a temperature below that of complete miscibility of the material with the wet solvent, but substantially above that of freezing of the material, to dissolve a substantial amount of the first-mentioned component and to leave a substantial amount of the second-mentioned component undissolved, then separating the two liquid phases from each other and removing the solvent and water from them to obtain the desired fractions.

2. A process as defined in claim 1 in which the solvent is further admixed with a hydrocarbon which is immiscible therewith, but is miscible with the material to be fractionated.

3. A process as defined in claim 1 in which the temperature at which the separation of the

phases is effected is about 5 to 50° C. below that of complete miscibility of the system.

4. A process as defined in claim 1 in which the polar solvent is acetone.

5. A process as defined in claim 1 in which the material treated is a free fatty acid.

6. A process as defined in claim 1 in which the material treated is a glyceride oil.

7. A process as defined in claim 1 in which the solvent is furfural.

8. A process as defined in claim 1 in which the solvent is acetone.

9. A process as defined in claim 1 in which the solvent is selected from a group consisting of the compounds in Tables A and B.

10. A process as defined in claim 1 in which the material treated is from a class consisting of soya bean oil, cottonseed oil, linseed oil and coconut oil.

11. A process as defined in claim 1 in which the component of the oil of high polar moment is relatively highly unsaturated and the component of low polar moment is more completely saturated.

12. A process as defined in claim 1 in which the component of the oil of high polar moment comprises a glyceride of an acid of relatively short chain length and the component of low polar moment comprises a glyceride of an acid of relatively long chain length.

JOHN D. JENKINS.
